Sugars and the

and thus provide an effective seal against the escape of lubricant at that point. Preferably, and as shown, the upper ends of the channel at opposite sides of the sump, terminate in gasket confining walls 36.

Advantageously and as shown a flared portion 37 of the lower arm, terminating at its free end contiguous opening 27 in a rib 38, is formed to oppose in spaced relation an inclined portion 39 of the sump extending from the channeled inner end 33, which constitutes a sealing section, to a bottom portion 40 thereof underlying the lower arm opening.

Formed on the outer end wall 32 of the sump and projecting toward the interior thereof at opposite sides, are two pairs of riblike lugs 41 and 42, having upper seating surfaces spaced downwardly from the upper extremity of the outer end wall 32 and adapted to underlie and engage seating surfaces 43 and 44 of a luglike formation 45 at the outer end wall of the lower arm. And, of importance, intermediate the pairs of riblike lugs 41 and 42, and the channeled inner end 33 there is provided a clamping means by which the sump may be drawn firmly into a clamped and secured position relative to the lower arm and effectively close the lower arm opening.

This clamping means, as shown, includes a pair of bolts 47 and 48 respectively passed upwardly through the bottom of the sump, through a pair of suitably bored upstanding lugs 49 and 50 and into threaded bores in a pair of lugs 51 and 52 formed on opposite sides of and extending laterally towards the interior of the lower arm 26 adjacent the opening 27. With this construction, it will be readily appreciated, when the bolts 47 and 48 are tightened, the channeled inner end 33 of the sump, constituting the sealing section thereof, is drawn upwardly with the riblike lugs 41 and 42 as a pivot or fulcrum section, and the gasket 35 is compressed and securely clamped in sealing relation between the channeled inner end and the lower arm. Moreover, it will be appreciated that the upward extending side and outer end walls 30, 31 and 32 respectively, provide effective barriers against the adverse escape of lubricant.

It will be understood that as in our Patent No. 2,299,439, lubricant from the lower and depending arms will be collected in the sump. It is intended in the operation of the lubricating system of a sewing machine embodying the present invention that the lubricant pump and the oil supply be so regulated that the level of lubricant in the sump shall be maintained in a position no higher than and preferably somewhat below the channeled inner end 33 of the sump.

In order that the lubricant collected in the sump may be properly filtered before being drawn back to the lubricant pump and distributed to operating instrumentalities, a generally cylindrical filter 53 of felt or the like is disposed to rest on the bottom portion 40 of the sump and to extend upwardly around and be spaced laterally from the lubricant conduit 28. And, of importance, there is provided a cover plate 54, having a hole 55 therein for receiving and closely confining the conduit 28, and adapted to overlie the filter 53.

Advantageously, and as shown best in Figs. 2 and 4, this cover plate 54 is so shaped and proportioned perimetricaly that it snugly fits in that portion of the sump laterally defined by the pairs of riblike lugs 41 and 42, and by the upstanding lugs 49 and 50. Thus, when the cover plate is

pushed downwardly in position it is snugly held in place, serves as a means for maintaining the filter 53 clamped tightly against the bottom portion of the sump, and forms with the filter and with the bottom portion of the sump an enclosed lubricant chamber 56 from which is effectively excluded dirt and other foreign matter which would impair the effectiveness of the lubricant. Moreover, to facilitate the flow of lubricant into the conduit 28, the latter is formed with an angularly extending side opening 28' at the free end thereof.

Also of importance, and as shown best in Figs. 1 and 2, the cover plate 54 is formed with a depending finger 58 adapted to rest on the bottom portion 40 of the sump adjacent a glass closed sight opening 59 provided in the side wall of the sump. This finger 58, which advantageously may be colored to readily contrast with the lubricant, thus serves not only as a stop or support for the cover plate, but also serves as a lubricant level indicating gage which may be observed through the sight opening. If desired, and as shown in Fig. 2, suitable indicia may be provided on the finger to further facilitate the ready determination of the lubricant in the sump.

In Figs. 7 and 8 a modified form of the invention is shown, which in all particulars except as pointed out hereinafter, is exactly the same as that form of the invention illustrated in Figs. 1-6 and described above.

This modified form of the invention differs from the form first described in providing a construction wherein the gasket at the inner end of the sump may be eliminated and yet a very effective barrier provided against the adverse escape of lubricant at that point.

Thus, with the modified form, the sump is formed with a modified open inner end 60 formed, instead of with a gasket-receiving channel, with a flange 61 projecting toward the lower arm, and adapted to be received between a pair of beads 62 and 63 formed on and extending under and up the sides of the lower arm. As in the case of the construction first described, when the clamping means is tightened the inner end of the sump is drawn firmly toward the lower arm. Thus, in the modified form, when the clamping up operation is completed the flange 61 is disposed and securely held in position between the beads 62 and 63 on the lower arm. Advantageously, and as shown, a plurality of spaced projections 64, 65 and 66 are formed on the flange 61 to directly engage the lower arm and tend to insure a uniform or equally distributed seating relationship of the inner end of the sump and the lower arm.

With the modified construction, it is thus seen, and as shown best in Fig. 7, the lower arm bead 63 interiorly of the sump, serves as a baffle to lubricant mist within the sump. Similarly the flange 61, projections 64, 65 and 66 and bead 62 serve as baffles to the lubricant mist. And, since the lubricant is maintained at a level below the inner end of the sump, as by proper control of the lubricant pump and supply, there is no danger of a mass flow of lubricant past the baffles above described and a practical seal against the escape of lubricant is provided.

Importantly, with each of the illustrated forms of the invention it is to be noted that the upper faces of the lugs 49 and 50 associated with the clamping bolts, are disposed upwardly above the intended maximum level of lubricant in the sump so that lubricant cannot adversely seep down

the bolt holes therein along the bolts and out of the bottom of the sump.

Hence with both illustrated forms of the invention, a lubricant sump is provided, which is adapted to be readily removed or replaced relative to an opening in a sewing machine frame to facilitate access to devices in the frame; which is adapted to effectively prevent the adverse escape of lubricant; which supports and includes in organizational association therewith advantageous lubricant filtering, shielding and indicating means; and which cooperates with special interrelated means and a conduit for conducting lubricant to a pump and divers operating instrumentalities, in providing a lubricant chamber effectively guarding against the association of foreign matter with the lubricant to be drawn into the conduit.

Other variations and modifications may be made within the scope of this invention and portions of the improvements may be used without others.

Having thus described the invention, what is claimed as new is:

1. In a sewing machine the combination of a frame having an opening; a cover plate for said opening having a portion thereof forming a pivot section for engaging the frame and a sealing section spaced therefrom; and clamping means disposed intermediate said pivot and sealing sections for causing the cover plate to pivot about the pivot section and move the sealing section into sealing relation with the frame.

2. In a sewing machine the combination of a frame having an opening and at least one bolt-receiving means within the field of said opening; a cover plate for said opening having a portion thereof forming a pivot section for engaging the frame, a sealing section spaced from the pivot section and a bolt-receiving section; and bolt means in said bolt-receiving section for causing the cover plate to move about the pivot section to bring the sealing section into sealing relation with the frame.

3. In a sewing machine the combination of a frame having an opening; a sump for covering said opening; securing means for the sump disposed only intermediate the ends of said sump for clamping the sump to the frame; a lubricant conduit; a seepage member of fibrous material resting in said sump and surrounding said conduit; and a plate having a port accommodating said conduit and covering said seepage member, said plate being held against inward movement and pressing the seepage member into engagement with the bottom of the sump when the securing means moves the sump into clamping relation with the frame.

4. In a sewing machine the combination of a frame having an opening; a sump member having a pivot section for engaging the frame and a spaced seal section with a generally upwardly facing channel; a gasket in said channel; and means disposed intermediate said sections adapted to concurrently move said sump member about the pivot section and to clamp the gasket between the frame and the channel in the seal section of the sump.

5. In a sewing machine the combination of a frame having an opening; a closure plate for said opening, providing a lubricant sump; opposed seating portions on said plate and said frame, located adjacent one end of said plate; a pair of clamping members extending through said clo-

sure plate and into association with said frame; said members being located intermediate opposite ends of said plate; supporting lugs for said members, on said closure plate; a conduit for conducting lubricant from said sump to an operating instrumentality in said frame; a filter in said sump encircling said conduit; and a cover plate, overlying said filter and through which said conduit extends, wedged in said sump intermediate said supporting lugs and the seating portions at one end thereof.

6. In a sewing machine the combination of a frame having an opening in the under portion thereof at one end; a troughlike closure member, providing a lubricant sump, and having a closed outer and an open inner end, said closed end extending upwardly to overlap said frame adjacent said opening; seating means on said closure member, adjacent said closed end and spaced downwardly from the upper extremity thereof for engaging the frame; means on said frame, opposed to said seating means; and screw means, disposed within said sump intermediate said seating means and inner end for holding said closure plate to said frame and for moving said closure plate with said seating means as a pivot to draw said open inner end up into clamping relationship with said frame.

7. In a sewing machine for combination of a main frame having a sump with a transparently closed sight opening therein; a conduit extending to said sump; a filter member in said sump, encircling said conduit; a cover plate on said filter and through which said conduit extends; and a depending finger on said plate, visible through said sight opening, supporting said plate relative to said sump and adapted to serve as gage of the level of lubricant in said sump.

8. In a sewing machine the combination of a main frame having a sump with a wall; a conduit extending to said sump, for conducting oil to an operating instrumentality in said frame; a filter member on said wall in said sump, encircling said conduit; a cover plate on said filter and through which said conduit extends, defining with said wall and filter a foreign matter excluding chamber for lubricant for said conduit; and a depending finger on said plate for engaging and supporting the latter relative to said sump.

9. In a sewing machine the combination of a frame having a sump with a wall and having a transparently closed sight opening therein; a conduit for lubricant, extending to said sump; a filter member on said wall in said sump, encircling said conduit; a cover plate on said filter and through which said conduit extends; and a depending finger on said plate, visible through said sight opening, of a color contrasting with that of the lubricant, and adapted to facilitate the determination of the level of lubricant in said sump.

10. In a sewing machine the combination of a frame having an opening; a sump adapted to close said opening, having a closed outer and an open inner end; opposed seating means on said frame and sump adjacent the outer end of the latter; a bead on said frame; a flange on said inner end, adapted to overlap said bead; and clamping means for drawing said sump relative to said frame, with said opposed seating means in engagement and forming a pivot and with said flange clamped to said frame and in overlapping relation with respect to said bead.

11. In a sewing machine the combination of a frame with an opening therein; a sump adapted

to close said opening, said sump having a seating section and a clamping section; spaced beads on said frame; a flange on said clamping section; and means in said sump intermediate said seating and clamping sections, for drawing said sump relative to said frame and moving the clamping section about the seating section as a pivot and clamping the flange to said frame intermediate said beads.

12. In a sewing machine the combination of a frame with an opening therein; a sump adapted to close said opening, said sump having a seating section and a clamping section; a bead on said frame; a plurality of spaced projections on said clamping section, projecting towards said frame; and means in the sump intermediate said seating and clamping sections, for drawing said sump about the seating section and relative to said frame with said projections clamped relative to said frame.

13. In a sewing machine the combination of a frame with an opening therein; a sump adapted to close said opening, said sump having a seating section and a clamping section; a bead on said frame; a plurality of spaced projections on said clamping section, projecting towards said frame; and means in the sump intermediate said seating and clamping sections, for drawing said sump about the seating section and relative to said frame with said projections clamped relative to said frame.

14. In a sewing machine the combination of a frame with an opening therein; a sump adapted to close said opening, said sump having a seating section and a clamping section; a bead on said frame; a plurality of spaced projections on said clamping section, projecting towards said frame; and means in the sump intermediate said seating and clamping sections, for drawing said sump about the seating section and relative to said frame with said projections clamped relative to said frame.

15. In a sewing machine the combination of a frame with an opening therein; a sump adapted to close said opening, said sump having a seating section and a clamping section; a bead on said frame; a plurality of spaced projections on said clamping section, projecting towards said frame; and means in the sump intermediate said seating and clamping sections, for drawing said sump about the seating section and relative to said frame with said projections clamped relative to said frame.

tive to said frame and in overlapping relation with respect to said bead.

13. In a sewing machine, the combination of a frame having an opening in the under portion thereof at one end; a troughlike closure member for said opening having a closed outer end extending upwardly to overlap said frame adjacent said opening and an open inner end, said troughlike closing member providing a lubricant sump for the machine, the closure member having inwardly projecting means on its closed end for engaging the bottom of the frame; and draft means intermediate the inner and outer ends for causing the closure member to pivot about the closed end and move the open end into abutting sealing relation with the underside of the frame.
